(57) **CLAIM**

The ornamental design for a folding trolley basket, as shown and described.

DESCRIPTION

FIG. 1 is a perspective view of the folding trolley basket showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the folding trolley basket is folded.

The broken lines in the drawings depict portions of the folding trolley basket that form no part of the claimed design.
